HEAT-FUSIBLE SAFETY LINK FOR INSERTION WITHIN A HOT-AIR CONDUIT OF A HEATING SYSTEM

Albert M. Smith and Edward Hart,
Columbus, Ohio

Application March 25, 1946, Serial No. 656,814

4 Claims. (Cl. 126—287.5)

1

Our invention deals with safety devices for furnaces and, more specifically, to devices of the character embodying a fusible link adapted, upon over-heating conditions within a furnace, to close a draft door and thereby reduce the operating temperature of the associated furnace.

In the operation of coal furnaces, it frequently occurs that the draft door is accidentally left open for a sufficient length of time to permit of over-heating within the system. Such a condition is necessarily hazardous in that, if allowed to continue, the overheating may easily result in a fire, or at least render serious damage to the furnace system.

It is, therefore, the general object of our invention to provide a device for automatically closing the draft door of a furnace, when the same has been accidentally left open for a period of time sufficient to occasion an overheating condition within the furnace.

It is another object of our invention to provide a device of this character which is structurally simple and consequently inexpensive to manufacture.

It is a further object of our invention to provide a device of this character which may be easily installed and replaced within any standard coal furnace without necessitating the services of a repairman particularly skilled in furnace operations.

For a further and more complete understanding of our invention, reference is made to the following description and the accompanying drawings, wherein:

Fig. 1 is a diagrammatic elevational view showing our present improved heat-fusible link operatively installed within a hot air conduit of a fuel burning furnace; Fig. 2 is an enlarged fragmentary vertical sectional view taken through a portion of a hot air conduit in which the present heat-fusible link is operatively installed; and Fig. 3 is a detailed perspective view of the present heat-fusible link.

With reference to the drawings, it will be seen that our invention embodies a fusible link comprising a V-shaped member 10 formed of semiresilient metal wire, and a central hook element 11 united with the V-shaped member 10, at its apex, by a fusible heat-softening material 12, such as solder having a comparatively low melting point. The central hook element 11 also carries a circular stop collar 13 substantially above and beyond the arms of the V-shaped member 10.

In operation, the lower portion of the link is

inserted through a small aperture 14 drilled in one of the hot air conduits 15 of a furnace in proximity to the plenum chamber 15a. When inserting the lower portion of the link within the conduit, the arms of the resilient V-shaped member 10 are squeezed together so as to permit of free entrance through the aperture 14, and once the upper ends of the arms are through the aperture and within the conduit, they will immediately spring apart to their normal position and thereby retain the link within the conduit. Thus it will be seen that the lower end of the link containing the soldered union will be maintained internally of the conduit and the outer hook element will be positioned externally thereof by means of the action of the stop collar 13.

Normally, a furnace is supplied with a remotely located manual control which operates, by means of chains and pulleys, the draft door of the furnace. In such a system, the pulleys or guides are usually located above the furnace and are attached to the under surface of a floor.

In using our improved fusible link, the outer end of the hook element 11 has bent engagement 25 with one end of a flexible chain 16 which, in turn, is passed through a screw eye 17 attached to a rafter or the underside of a floor 18. The opposite end of the chain is then rigidly attached to and supports a detached pulley 19 substantially in 30 the same position as the latter would normally occupy when attached to the rafter. Thus the normal manual control of the draft door is not interfered with by the addition of our safety device.

It will be manifest that if overheating occurs within the furnace and the conduit 15, due to the draft door being accidentally left open, the subsequent high degree of heat transmitted to the solder union will melt same and free the hook element 11 from the V-shaped member 10, and thus allow the pulley 19 to drop from its normal position and allow the draft door to close.

To prevent the chain 16 and its attached pulley 19 from dropping completely to the floor upon 45 the breaking of the link, a stop 20 is carried by the chain and positioned thereon so as to allow the pulley to drop only the distance sufficient for the closing of the door before the stop engages the screw eye 17.

In view of the foregoing, it will be seen that our invention contemplates a highly efficient and structurally simple fusible link to be utilized as a safety feature for standard furnaces. It will also be noted that the installation of such a link 50 may be easily accomplished utilizing the normally

installed equipment of a standard furnace, and that by simply drilling a small hole within a hot air conduit, inserting the link, and attaching the chain to the pulley, the complete system may be accomplished by one not necessarily skilled in the repair or maintenance of furnaces. It will be manifest that the temperature at which the link will part may be controlled by the melting point of the fusible material used. It has been found desirable, when the link is positioned within the conduit, as shown in the drawings, that the melting point of the solder be in the neighborhood of 260° F.; however, it will be understood, in view of the following claims, that our invention is neither limited by the positioning of the link with respect to the various parts of the furnace, nor is it limited by the use of any one fusible material as each of these factors are necessarily dependent on one another, and may be varied to adapt the link for use under individual circumstances.

While we have disclosed what we now deem to be the preferred form of our improved fusible link, it will be manifest that various changes in design and details of construction may be later accomplished without departing from the spirit of the invention or the scope of the following claims.

We claim:

1. In combination with a hot air conduit of a furnace, a fusible link comprising an elongated metallic rod formed at one end with a hook, and a V-shaped barb member united with the opposite end of said rod by a fusible heat-softening material, said barb member being located within said conduit and being formed with a pair of angularly related resiliently movable arms extending backwardly along said rod and terminating in end portions disposed in spaced longitudinal angular relation to said rod, the arms of said barb member being resiliently movable into substantially parallel positions alongside of said rod to permit insertion thereof through a relatively small opening formed in said conduit, and when once inserted being adapted to spring apart and engage the inner wall of the conduit to prevent withdrawal of said link through such opening prior to the softening of the material uniting said barb member with said rod.

2. A heat fusible link for insertion within a hot air duct of a furnace system, comprising an elongated rod formed at one end with a hook, and a V-shaped barb member united at its apex with the opposite end of said rod by a fusible heat-softening material, said barb member being formed with a pair of resilient spring arms radiating outwardly from the apex of said member and backwardly in longitudinal angular relation to said rod and terminating in normally spaced apart relation intermediate the length of said rod, the arms of said barb member being

resiliently movable toward one another into substantial parallelism with said rod to permit of insertion of said link through a relatively restricted opening formed in a hot air duct, and being separable under resilient tension after initial insertion within the air duct to retain said link therein against withdrawal.

3. A fusible link for insertion within a hot air conduit of a furnace system, comprising a substantially straight metallic rod formed at one end with a hook, and a V-shaped barb member united at its apex with the opposite end of said rod by a heat-fusible material and having a pair of resiliently movable arms radiating backwardly along said rod and terminating in end regions disposed in normally spaced longitudinal angular relation to the intermediate portion of said rod, the arms of said barb member being resiliently movable toward one another and into substantial parallelism with said rod to permit of insertion of said arms through a relatively restricted opening formed in a hot air conduit and to cause said arms to spring apart to their spaced angular positions with respect to said rod after insertion thereof within the hot air conduit to prevent withdrawal of said link from the conduit prior to the softening of the material uniting said barb member with said rod.

4. A fusible link for insertion within a hot air conduit, comprising a substantially straight rod provided at one end thereof with a hook, and a barb device carried at the opposite end of said rod by means of a heat-fusible material and formed with a pair of angularly related resiliently movable arms extending backwardly along said rod and terminating intermediately thereof in spaced angular relation to said rod, the arms of said barb device being resiliently compressible toward one another and into substantial parallelism with respect to said rod to permit the barb-carrying end of said rod to be inserted through a relatively restricted opening formed in the wall of a hot air conduit and to permit the arms of said barb device to spring apart after passing through the wall of the conduit to retain said rod against withdrawal therefrom prior to the fusing of the material uniting said rod with said barb device.

ALBERT M. SMITH.
EDWARD HART.
